UNITED STATES PATENT OFFICE.

HERMAN A. SCHULTZ, OF CHICAGO, ILLINOIS, ASSIGNOR TO CHARLES E. REED, OF THE TOWNSHIP OF MCHENRY, ILLINOIS.

COPYING LATHE.

Application filed March 29, 1924. Serial No. 702,812.

My invention relates, more particularly, to lathes provided for the manufacture of shoe-lasts and more especially graded shoe-lasts and of the type comprising, as an element, a swing-frame which, in lathes of this type as commonly provided, has revolvably mounted thereon the pattern and the work, to cooperate with a pattern-follower and the cutter, respectively.

10 The grading of the lasts to be produced by machines of this type is accomplished by the provision of mechanism controlled by the swinging movements of the swing-frame and operating to produce a differential movement of the pattern-follower relative to the cutting mechanism which operates on the work, and as the swing-frame moves in an arc, it is thus impossible to produce graded lasts from a pattern, which shall present exactly the same contour as the pattern but of enlarged, or diminished, size, as the case may be. Furthermore, even in the case of making a last of the pattern size it is not possible to produce such a last of exactly the same 25 contour as the pattern due to the swinging of the frame in an arc.

As machines have been hitherto provided, the error above referred to, especially in the case of the larger sizes of lasts produced, is so great as to present great objection in the manufacture of lasts, and it is my primary object to provide improvements in machines of the swing-frame type to the end that the error referred to and occurring in the lasts will be so minimized as to be practically negligible, the lasts produced, for all practical purposes, having the same contour as the pattern except of enlarged or diminished size in the case of graded lasts.

40 In explanation of the production of the objectionable error in the lasts above referred to in the case of machines as hitherto constructed, it may be stated that the parts of the machine are so proportioned and arranged that the swinging movements of the frame in the ordinary movements thereof in producing a last are wholly to one side of the vertical plane in which the pivot of the swing-frame extends, and this I overcome, generally stated, by so proportioning and arranging the parts that the frame in its swinging movements swings at opposite sides of such vertical plane.

Another object is to provide improvements in lathes of the general character above re-

ferred to to the end that the machine may be provided with a relatively short swing-frame, thus presenting a relatively short lever-arm, with consequent adaptability for practical operation at relatively rapid speed, 60 without causing the lasts produced thereby to present any greater degree of error above referred to, than is produced in machines as hitherto provided where a swing-frame presenting a long lever-arm, and consequently 65 requiring to be operated at relatively slow speed, is provided.

While my invention is applicable generally to machines of the type above referred to, I have devised it for embodiment more especially in a machine of the general construction shown in the pending application of Charles E. Reed for United States Letters Patent, Serial No. 650,194, filed July 7, 1923, and have therefore chosen to illustrate it in such machine without, however, intending to be understood as desiring to limit the invention thereto.

Referring to the accompanying drawings: Figure 1 is a view in front elevation of a machine of the general construction disclosed in the above referred-to pending application, showing the machine as equipped with my present improvement. Figure 2 is an end view thereof, viewing the machine from the right hand end in Fig. 1 and the swing frame swung out forwardly to locked in-operating position. Figure 3 is a plan view of the machine with the upper works thereof shown in section and the swinging frame removed. Figure 4 is an enlarged section taken at the line 4-4 on Fig. 1 and viewed in the direction of the arrows, the machine being shown in the position illustrated in Fig. 2; and Figure 5, an enlarged broken view of the upper swing-frame-equipped portion of the machine, the machine being viewed from the left hand side of Fig. 1, with certain parts removed, this view showing the swing-frame and its counter-weighting mechanism, by full lines in one of the positions they may occupy in the operation of the machine and by dotted lines another position in which they may extend.

Referring to the particular illustrated machine, which is adapted for the turning of lasts of the pattern size or graded, as desired, the same comprises a frame 25 provided adjacent its rear side with a guide-way 26 and adjacent its front side with upwardly-ex-

95

100

105

110

tending parallel guide-ways 27 and 28 arranged in overlapping relation as shown in Figs. 2 and 3, the frame being provided at its opposite ends, above these guide means, 5 with upwardly-extending standards 29 having forwardly curved extremities and brace-members 30. Mounted on the guide-ways 26 and 27 is a slide 31 which carries the cutting mechanism for cutting the work mounted in 10 the swing-frame, as hereinafter described, this cutting mechanism, corresponding with the cutting mechanism of the said pending application, involving, generally stated, a roughing-cutter 32 formed of a plurality of 15 toothed disks of successively larger diameters flatwise disposed on a shaft 33 driven from the shaft of a motor 34 secured on the slide 31, through the medium of a gearing (not shown) located in a gear-housing 35, 20 the cutting portion of the roughing-cutter 32 being of general frustro-conical form as shown. The cutting mechanism also comprises a finishing cutter represented at 36 formed of diametrically-opposed cup-shaped 25 cutters 37 and 38 mounted on a shaft 39 and driven from the gearing in the housing 35.

Mounted on the guides 26 and 28 for movement in a direction lengthwise of the machine, is a slide 40 provided with guides, extending crosswise of the machine, on which a slide 41 is mounted to be movable longitudinally thereon, the slide 41 carrying the pattern-follower represented at 42. The slide 41 is provided with a rearwardly-extending plate 43 (Fig. 4) mounted in a slide 44 vertically adjustable on the main body of the slide 41, the plate 43, opposing the front face of a plate 45 extending lengthwise of the machine and trunnioned at its opposite 40 ends, as represented at 46, to the frame to rock crosswise of the machine on a horizontal axis, the plate 45 being provided with an upwardly-extending arm 47 operatively engaging with mechanism hereinafter described for causing the plate 45 to be rocked, responsive to the swinging movements of the swing-frame hereinafter described and comprising a link 200 having pivotal connection at its rear end with the lever 47 as represented at 201, and similar connection at its forward end with the swing-frame referred to, as indicated at 202. The slide 41 is caused to bear, at its plate 43, at all times, against the front face of the plate 45, 55 through the medium of a spring 41^a which is attached at one end to the slide 41 and at its opposite end to the slide 40.

The slides 31 and 40 are operatively connected together through mechanism for causing them to move simultaneously in the same direction lengthwise of the machine, either at the same speed, to produce a last of the exact size of the pattern hereinafter referred to, or at different speeds, to produce graded 65 lasts, the said mechanism shown being the

same as that illustrated in the said pending application, and comprising, generally stated, a bar 48 pivotally connected at one end to the slide 31, as indicated at 49, this bar being formed of lengthwise-adjustable sections 50 and 51 to vary the effective length of the bar 48. The end of the bar 48 opposite that at which it connects with the slide 31 is pivotally connected, as indicated at 52, with the upper end of a rack bar 53 slidable 75 up and down in a bar 54 slotted at its lower end, as indicated at 55, through which slot the pivoting stud 56 of a clamping device carried by a stationary bar 58 and adjustable up and down on the latter, extends, the 80 bar 58 being rigidly connected, at its opposite ends, with the frame of the machine, as shown. The bar 53 is pivotally supported on the slide 40 through the medium of a pivot 59 and carries a rack (not shown) 85 which meshes with a pinion (not shown) in a gear-case 60 carried by the bar 54, the pinion referred to being rigidly secured to a shaft 61 which is provided with a crank-handle 62 through the medium of which 90 this pinion may be rotated to adjust the bar 53 lengthwise of the bar 54, it being understood that by varying the relatively movable members forming the connecting mechanism described, the slides 31 and 40 may be moved simultaneously at the same speed for the production of a last of the same length as the pattern, or different speeds, to produce longer or shorter lasts, as desired. The mechanism for moving the slides 31 and 40 100 lengthwise of the machine to feed the pattern-follower and the cutting mechanism along the pattern and work, respectively, mounted in the swing-frame referred to, comprises, in the particular construction 105 shown, a shaft 63 journaled in a bearing 64 which has slight rocking movement in a vertical plane on the frame of the machine, one end of this shaft carrying pulleys 65, connected by a belt 66, with pulleys 67 secured to a shaft 68 forming the main driving shaft of the machine and driven from a motor represented at 69. The other end of the shaft 63 carries a worm 70 which meshes with a 110 worm-wheel 71 secured to a shaft 72 journaled on the frame of the machine and meshing with a rack depending from the slide 31, the parts being so constructed and arranged that when the worm 70 meshes with the worm-wheel 71, the slide 31 will be driven from the shaft 63 to the left in Fig. 1, and through the medium of the lever mechanism 115 hereinbefore described and connecting the slide 31 with the slide 40, the latter will be simultaneously moved in the same direction with the slide 31, at the same speed, or at a different speed therefrom, depending upon the setting of the said lever mechanism. The machine shown is provided with means for 120 effecting the automatic arresting of the drive 125. 130

for the slides 31 and 40 at the conclusion of the operation of forming a last, but as the present invention has nothing to do with this feature of the machine, a detailed description thereof is omitted.

Referring now to the swing frame of the machine and hereinafter referred to, this frame is represented at 73, and forms a swinging support for the pattern 74 and the wood-blank 75, from which a last is to be formed, which are rotatably mounted therein, and in the operation of the machine are rapidly rotated, all as hereinafter described. The swing frame 73 is journaled, in the particular construction shown, at its upper ends on the frame standards 29 at hollow trunnions 76 secured in the upper ends of the side arms 77 of the swing frame 73. The trunnions 76 form journals for a shaft 78 extending therethrough and carrying the stepped pulleys 79 through the medium of which it is driven to rotate the pattern 74 and work 75, as hereinafter described, by the belt connection 80 with other belt pulleys 81 secured on the shaft 68. The pattern 74 is mounted on a head-stock 82 and a tail-stock 83, and the work 75 is mounted on a head-stock 84 and a tail-stock 85, to respectively oppose the pattern-follower 30 and cutting mechanism hereinbefore referred to. The means shown, and which are the same as those of the herein-before-referred-to pending application, for rapidly rotating the pattern 74 and work 35 75, either in the same, or opposite, directions, as desired, comprise, generally stated, a shaft 86 journaled on the frame and geared to the spindles of the head-stocks 82 and 84 to cause the spindles to operate simultaneously, by gearing located in housings 87 and 88 on the frame 73, and a shaft 89 connected with the gearing referred to and journaled on this frame. The shaft 86 is driven, through the medium of bevel gears (not shown) located in the housing 90, through the medium of a shaft 91 having bevel gear connection at 92 with the shaft 78.

In accordance with my invention, as hereinbefore stated, the parts of the structure 50 are so proportioned and arranged that the swing frame 73, in the operations of turning a last, swings alternately from one side to the other, of the vertical plane in which extends the axis about which the frame 73 swings, it being preferred that the parts be so proportioned and arranged that the frame 73 in the operations of turning a last such as those of the form now commonly manufactured, will swing, in its extreme movements, substantially the same distance, at opposite sides of the said vertical plane. I have found it desirable to so locate the axis upon which the frame 73 swings, that the aligned axes about which the pattern and work rotate extend to the left of the vertical

plane in which extends the axis about which the frame 73 swings, a distance of approximately one and a half inches, when these aligned axes are co-incident with the extreme forward point on the follower, as illustrated by the full lines in Fig. 5, assuming that the follower is lined up with the cutting mechanism. Such disposition of the parts very materially reduces the error above referred to, but to still further minimize such error the portions of the head and tail stocks in which the pattern and work are mounted are so disposed that their aligned axes will extend a slight distance below the forwardmost point on the follower when the swing-frame is in vertical position. By way of example and assuming that the distance from the axes of the work and pattern to the pivotal support of the swing frame is the same as in machines as now commonly provided, the axes of the work and pattern would preferably extend below the plane in which the forwardmost point of the follower extends, about $1/64$ of an inch, when the swing frame is in vertical position.

In explanation of the advantages of so locating the axis about which the swing frame 73 extends that the swing frame will swing to both sides of the vertical plane in which its pivoted axis extends, as above described, it may be stated that the ideal arrangement, from the standpoint of fully eliminating error in the lasts, would be to mount the pattern and the work on a member which would slide in a straight line toward and away from the follower and cutting mechanism. However, in practice it is desirable to use a swing-frame for the pattern and the work, and thus the pattern and the work move through an arc-shaped path, and when the parts are disposed in accordance with my invention as above described, the distance through which the pattern and work move in a vertical path is very greatly reduced compared with the distance through which these parts move when the swing-frame, in the cutting operations, swings to one side only of the vertical plane in which the axis upon which the swing frame swings, extends. In designing a machine to embody my invention, the designer, to properly locate the axis about which the swing-frame swings, relative to the pattern-follower, would first determine the length of the arc through which the pattern and the work move in the movement of the frame from one to the other of its extreme positions in the cutting of lasts of the form commonly produced, and then locate the axis of the swing-frame so that when this frame is in the full line position shown in Fig. 5, in which position the aligned axes of the pattern and the work are substantially coincident with the forward point on the follower, these aligned axes will extend to the left of

the vertical plane in which the pivoted axis of the swing-frame is located, a distance equal to substantially one-half of the length of the arc referred to.

5 It is necessary that the pattern 74 press against the pattern-follower 42 at all times, in the operation of the machine, whereby in the rotation of the pattern the frame 73 is caused to oscillate by virtue of the rotation 10 of the pattern against the follower, to the end that the blank, or work 75, will, in its rotation, be cut to present the same form as the pattern. The particular illustrated mechanism for this purpose comprises a belt 15 93 at each end of the machine, the forward end of each belt being connected with the lower portion of the frame 73 at each end thereof and extending over pulleys 94 fixed on the ends of a shaft 95 journaled on the 20 frame of the machine and provided with a sprocket 96 connected by a sprocket chain 97 with a sprocket 98 secured to the shaft 78, the shaft 95 being thereby rotated in clockwise direction in Fig. 2. The belts 93 extend 25 from the pulleys 94 to pulleys 99 rotatably mounted on shaft 100 and are provided at their free ends with weights 101.

The weighted belt devices described, by reason of the constantly rotating shaft 95, 30 operate to exert against the swing-frame 73, at all times, force in a direction to swing the frame 73 in counter-clockwise direction in Fig. 2 and serve to exert a snubbing action on the frame, preventing rebounding of the latter away from the pattern-follower and the cutting mechanism.

Inasmuch as it is desirable that the swing frame 73 be yieldingly forced toward the follower and cutting mechanism with substantially the same force, regardless of the position in which the swing-frame extends, and inasmuch as the swing-frame 73, when it extends to the left of the vertical plane in which the pivotal axis of the swing-frame is located, as represented by full lines in Fig. 5, will tend to swing to the right in this figure and consequently away from the pattern-follower and cutting mechanism and when this frame swings to the right of said 40 vertical plane, as shown by dotted lines in Fig. 5, it will tend to swing toward the pattern-follower and cutting mechanism, means are shown for compensating for this condition, these means, which, however, 45 form no part of my invention as they were devised by one Charles E. Reed and form the subject of an application for United States patent Serial No. 702,813 filed by him on March 29, 1924, and copending herewith 50 comprise the following described mechanism: Rigidly secured to the ends of the shaft 100 are upwardly-extending levers 102 each provided with a weight 103 at its upper end, these levers being similarly positioned on the shaft 100 and each connected,

through the medium of a link 104 pivoted thereto at 105, with levers 106 rigidly secured to the ends of a shaft 107 journaled in the frame of the machine. The connections between the link 104 and the levers 106 are pivotal as represented at 108 and located between the ends of these levers, and the pivotal connections 105 are likewise located between the ends of the levers 102. The upper ends of the levers 106 are pivotally connected with rods 109, the forward ends of which are pivotally connected with the lower ends of the swing-frame 73 at the opposite ends of the latter, the shaft 107, levers 106 and rods 109 forming equalizers 75 80 insuring against deflection of the swing-frame in the operations of the machine. It will be noted that in the particular construction shown the distance from the pivot points 105 to shaft 100 is much less than the 85 distance from the pivot points 108 to the shaft 107, whereby the leverage is compounded thus causing the levers 102 to swing through greater arcs, than the swing-frame, and thereby effectively counterbalancing the 90 latter.

The lever mechanism just described, and as shown, is so arranged that when the swing frame is in vertical position the levers 102 extend vertically upward and when this 95 frame extends to the left in Fig. 5 as shown in full lines, these levers extend to the left as shown in full lines, and when the swing frame extends to the right of the vertical as shown by dotted lines, the levers 102 also 100 extend to the right of this figure as shown by the dotted lines, the levers 102 thus serving to substantially counterbalance the force exerted by gravity against the swing frame and tending to swing the latter to vertical 105 position. While the arrangement is such as shown and described that when the swing frame is vertical the levers 102 are vertical, it may be found desirable, under some conditions, to so modify this arrangement that 110 the levers 102 will be slightly inclined in one direction, or the other, when the swing frame is vertical.

It will be understood from the foregoing that in the illustrated embodiment of my invention, the force exerted by the frame in the direction of the pattern-follower and cutting mechanism is determined by the force exerted on the belts 93 which, in the preferred construction shown, depends on 120 the speed at which the shaft 95 rotates and the weight of the bodies 101.

While I have illustrated and described a particular construction embodying my invention, I do not wish to be understood as 125 intending to limit it thereto as the same may be modified and altered without departing from the spirit of my invention, and, as will be readily understood, the invention may be incorporated in a machine in which 130

the swing-frame is pivotally supported below the axes of the work and pattern, as well as in a machine in which the pivotal support is above said axes.

5 What I claim as new, and desire to secure by Letters Patent, is:

In a last lathe structure, the combination of a pattern-follower and cutting mechanism, a swing-frame supporting a pattern and the work for cooperation with said

follower and cutting mechanism, respectively and grading mechanism with which the swing-frame and pattern-follower are connected, the axis upon which said frame swings being so located that said frame, in 15 the cutting operation of the machine, swings to both sides of the vertical plane in which said axis is located.

HERMAN A. SCHULTZ.
